UNITED STATES PATENT OFFICE.

ROBERT H. READ AND WILLIAM C. YATES, OF SCHENECTADY, NEW YORK,
ASSIGNORS TO GENERAL ELECTRIC COMPANY, A CORPORATION OF
NEW YORK.

TIME-LIMIT STARTING AND CONTROLLING RHEOSTAT.

SPECIFICATION forming part of Letters Patent No. 783,462, dated February 28, 1905.

Application filed July 21, 1904. Serial No. 217,440.

To all whom it may concern:

Be it known that we, ROBERT H. READ and WILLIAM C. YATES, citizens of the United States, residing at Schenectady, county of 5 Schenectady, State of New York, have invented certain new and useful Improvements in Time-Limit Starting and Controlling Rheostats, of which the following is a specification.

This invention relates to rheostats for starting and controlling variable-speed electric motors; and its object is to provide a device of this kind in which the operator will be prevented from holding the switch-arm for any length of time upon an intermediate point of 15 the starting resistance, and thereby damaging the apparatus by the excessive heating of the coils. There is a proper speed of movement for the switch-arm of a starting-rheostat, and the present invention enforces on the operator an observance of this speed by open-circuiting the retaining-magnet of a main circuit-breaker incorporated in the apparatus if he actuates the arm too slowly.

In the accompanying drawings, Figure 1 is 25 a front elevation of the apparatus. Fig. 2 is a diagram of circuits, and Fig. 3 is a detail side elevation of the main brush.

The working parts are mounted on a suitable panel 1, through which passes a shaft 2, 30 to which is secured an arm 3, carrying a laminated brush 4, one end of which makes contact with a number of contact-segments arranged concentric with the shaft. The first segment 5 is "dead." The next few segments 35 6 are those connected with the coils 6' of the starting resistance. The succeeding segments 7 are connected with the coils 7' of the running or controlling resistance. The other end of the brush 4 bears on a long broad segment 40 8, which is cut away at the left-hand end to make room for a short insulated segment 9, the gap between these two segments being bridged by the wide end of the brush 4 when it stands over them, as shown in Fig. 3. The 45 arm 3 also carries a light spring-brush 10, electrically connected with the main brush and bearing on a long contact segment or

strip 11. The brushes 4 and 10 are insulated from the arm 3.

In line with the segment 11 is a set of contact segments or buttons 12, connected with the coils 13 of a field-regulating resistance. A self-opening switch-arm 14 is pivoted to the panel 1 at 15 and carries a contact 16, which co-operates with a stationary clip 17. 50 This constitutes the circuit-breaker for the main circuit. It is rendered automatic by a retaining-magnet 18 of the usual construction. A quick-break switch 19 is pivoted near the main switch-arm and closes on a contact-stud 19'. It is operated by an insulated lug 20 on said arm just after the main brush leaves the first starting-segment 6 in moving to the "off" position on segment 5. The reversing-switch 55 comprises two insulated switch-blades 21 21', mounted on a pivoted hub 22, of insulation, and operating to bridge the opposite pairs of contact-clips 23 23' 24 24' or the clips 25 25' 26 26' by giving the hub a quarter-turn. This switch is interlocked with the main switch-arm, a spring-retracted bolt 27 being forced 60 into notches in the hub 22 by a cam 28 on the hub of the main arm except when the latter is in the off position, at which time the bolt is retracted and the reversing-switch can be 65 shifted. An overload-solenoid 29 operates a bridging-contact 30, which opens the circuit-breaker 14 by opening the circuit of the retaining-magnet 18 at the contact-studs 30' 30''. This magnet can also be short-circuited in 70 order to open the circuit-breaker by a time limiting device which constitutes the novelty 75 of the present invention. A lever 31 is pivoted concentric with the main switch-arm 3, and its outer end is connected by a rod 32 with a time 80 limiting device, preferably a dash-pot 33. A spring 34 tends to lift the lever at a rate governed by the dash-pot. The lever carries an insulated bridging-contact 35, co-operating 85 with two fixed contact-studs 36 36'. A horn 37 on the main switch-arm 3 strikes the lever and forces it downward when the switch is turned to the off position compressing the spring 34 and separating the contact 35 from 90

the studs 36 36'. A lug 38 on the main arm, preferably carrying an antifriction-roll 39, strikes the circuit-breaker 14 and closes it when the arm 3 is moved to the extreme left.

5 The circuits are as follows: The line-terminals are seen at 40 40'. The field-coil of the motor is connected with the studs 41 41' and the armature with the studs 42 42'. Terminal 40' is connected directly with the clip 17. Terminal 40 is connected with field-stud 41' and also with the contact-stud 30'. It is also connected with the clips 23' 24'. The clips 25' 26 are connected, through the overload-solenoid 29, with the last segment 7. The clips 23 25 15 are connected with the armature-stud 42 and the clips 24 26 with the stud 42'. The field-stud 41 is connected with the contact-strip 11. The first starting-resistance segment 6 is connected with the final field-resistance segment 20 12 and also with the contact-stud 19'. The quick-break switch 19 is connected with the contact-strip 8, and the latter is connected, through the pivot 15 of the circuit-breaker 14, with one terminal of the retaining-magnet 18.

25 The other terminal of said magnet is connected, through a resistance 43, with the contact-stud 30'. It is also connected with the contact-stud 36, the other stud, 36', being connected with the contact-segment 9.

30 The operation is as follows: When the switch-arm 3 is moved to the extreme left, the roll 39 strikes the circuit-breaker 14 and closes it upon the clip 17, thereby completing the circuit through the retaining-magnet 18 by way of the resistance 43, contact-studs 30' 30', and contact 30. The circuit of the motor is still open, however, at the interval between the dead segment 5 and the first starting-segment 6 and also at the quick-break switch 19, 35 which has been swung away from the contact-stud 19' by the lug 20 on the main arm 3. The movement of the arm 3 has also forced down the lever 31 and compressed the spring 34 and opened the short-circuiting contact 35.

40 It has also released the spring-bolt 27 and unlocked the reversing-switch. The latter having been thrown to give the desired direction of rotation to the motor, the arm 3 is moved to the right, locking the reversing-switch again. Just before the brushes pass onto the first starting-segment 6 the switch 19 closes the motor-circuit, so that all sparking takes place at the contact 19', and thus the brushes are protected. Now that the horn 37 45 has been withdrawn from the lever 31 the spring begins to lift said lever, being retarded by the dash-pot, which is set to allow a given time—say thirty seconds—to elapse before the contact 35 will bridge the studs 36 36'. During this time the operator must move the arm 3 over the starting-segments 6 and the contact-segment 9 and reach the running-segments 7 and the contact-strip 8. If he is too slow and is caught with the brushes on the 50 segment 9 when the contact 35 closes, the re-

taining-magnet 18 is short-circuited by way of the contacts 35 36 36', segment 9, brush 4, strip 8, and pivot 15. This releases the circuit-breaker, which can be reset only by returning the main arm to the extreme left.

In case of an overload the solenoid 29 lifts the contact 30 off the studs 30' 30", and thus breaks the circuit of the no-voltage magnet 18.

To stop the motor, the arm 3 is moved back to the dead segment 5. The circuit-breaker 75 opens the instant the arm makes contact with the strip 9, which is before the brushes leave the first of the starting-segments 6. When the motor is running, the field-coil and armature are in multiple, each having its own resistance in circuit; but when the arm 3 is turned back to the segment 5 and the circuit-breaker is open the field-coil and armature are placed in a closed circuit in series with each other and with all the resistances, so that 80 the motor, running as a generator by its own momentum, quickly comes to rest.

What we claim as new, and desire to secure by Letters Patent of the United States, is—

1. The combination with a rheostat comprising starting and running resistances, of a circuit-breaker, and means for tripping said circuit-breaker within a predetermined time if the operator fails to move off the starting resistance within said time.

2. The combination with a rheostat comprising starting and running resistances, of a circuit-breaker, and means for tripping said circuit-breaker within a predetermined time if the operator fails to move off the starting 95 resistance within said time, said means comprising a dash-pot and a switch controlled thereby.

3. The combination with a rheostat comprising starting and running resistances, of a circuit-breaker, and means for tripping said circuit-breaker within a predetermined time if the operator fails to move off the starting resistance within said time, said means comprising a short circuit containing two breaks, 105 one controlled by the rheostat-arm, a switch controlling the other break, and a dash-pot governing the closing of said switch.

4. The combination with a rheostat comprising a switch-arm, of a circuit-breaker comprising a no-voltage retaining-magnet, a switch for short-circuiting said magnet adapted to be opened by said arm, and a dash-pot controlling the closing of said switch.

5. The combination with a rheostat comprising a switch-arm, of a circuit-breaker comprising a no-voltage retaining-magnet, a short circuit for said magnet controlled by said arm, a switch in said short circuit adapted to be opened by said arm, and a dash-pot controlling 110 the closing of said switch.

6. The combination with a rheostat comprising a switch-arm, of a circuit-breaker comprising a no-voltage retaining-magnet, a short circuit for said magnet controlled by said arm, 115

a lever pivoted concentric with said arm and carrying a contact controlling said short circuit, means whereby said arm can actuate said lever, and a dash-pot connected with said lever.

5 7. The combination with a rheostat comprising a switch-arm, of a switch adapted to be opened by said arm when moved to the "off" position, a dash-pot controlling the closing of said switch, and a circuit-breaker controlled by said switch.

8. The combination with a rheostat comprising a starting resistance and a running resistance, of a switch-arm coöperating therewith in succession, a circuit-breaker comprising a no-voltage retaining-magnet, a short circuit for said magnet which is opened when said arm moves off the starting resistance, a

switch controlling said short circuit which is automatically opened when the arm is brought to the "off" position, and a dash-pot effecting a slow closure of said switch after the arm is moved away from the "off" position. ²⁰

9. The combination with a starting-rheostat, of means for opening the circuit independently of the operator, and a time-limit device ²⁵ controlling such opening throughout the starting positions.

In witness whereof we have hereunto set our hands this 19th day of July, 1904.
